UNITED STATES PATENT OFFICE

JOHN M. KELLER, OF LAKESIDE, OHIO

WINDOW SUPPORT

Application filed March 27, 1930. Serial No. 439,335.

This invention, relating as indicated to window supports, has specific reference to the construction of a window guide whereby the pane of glass is resiliently secured in the window jamb. The window guide comprising my invention is especially applicable to be used in connection with the slideable windows such as employed in automobiles, and the construction of the guide comprising my invention presents advantages not found in any guides heretofore constructed. It is among the objects of my invention to provide a guide having the above-named desirable characteristics. Other objects of my invention will appear as the description proceeds.

To the accomplishment of the foregoing and related ends, said invention, then, consists of the means hereinafter fully described and particularly pointed out in the claim; the annexed drawings and the following description setting forth in detail certain structure embodying the invention, such disclosed means constituting, however, but one of various mechanical forms in which the principle of the invention may be used.

In said annexed drawings:—

Fig. 1 is a transverse sectional view of a guide comprising my invention shown disassociated from the glass and the window jamb; Fig. 2 is a fragmentary sectional view of a window jamb and a window pane showing in assembled relation the guide comprising my invention; Fig. 3 is a transverse sectional elevation of the guide comprising my invention; Fig. 4 is a fragmentary elevational view of the rear of the guide; and Figs. 5 to 8, inclusive, are fragmentary sectional views similar to Fig. 2 showing respectively alternative forms of construction of the guide comprising my invention.

Referring more specifically to the drawings and more especially to Figs. 1 to 4, inclusive, the form of guide here shown consists of a one-piece element which is rolled or otherwise bent into the form shown in Fig. 1, in which a portion 1 of the element is substantially flat. The portions contiguous to the portion 1, that is the portions 2 and 3, converge outwardly in the manner illustrated and the edges of the one-piece ele-

ment are rebent into portions 4 which extend inwardly of the guide and which have their terminal portions rebent as at 5. The flat portion 1 has a plurality of resilient elements 6 struck up therefrom, which elements extend inwardly of the guide and present a resilient support for the edge of the pane. The guide may have apertures 7 formed therein adapted to receive securing means 8, which may be nails or screws or the like.

As illustrated in Fig. 1, the guide as formed from one piece of material has the portions 2 and 3 thereof converging outwardly from the base member 1, and the distance between the opposite faces of the portions 3 slightly greater than the space between the inner faces of the legs 9 of the channel or groove in which such guides are usually mounted. With the distance between the opposite faces of the portions 3 slightly greater than the width of the slot, the guide must be compressed slightly in order to be inserted in the receiving slot, and such compression provides the resiliency necessary to maintain the guide in proper assembled relation in the channel so that no rattling of the window occurs. When the guide is inserted in the groove provided therefor the portions 3 thereof will lie in substantially parallel planes so as to present flat contacting surfaces to the inner faces of the legs of the groove and these flat faces of the portions 3, along with the flat bearing surface of the portion 1 provide a rigid assembly of the guide in the groove or channel, which rigidity may be further insured by fastening the guide by means of nails or screws, as at 8.

As hereinbefore indicated, the portion 1 of the guide has resilient means struck up therefrom and extending inwardly into the guide so as to resiliently engage the edge of the pane. These struck-up portions are so formed that only relatively short distances at spaced points along the edge of the glass are engaged by the guide so that the frictional resistance between the guide and the glass is reduced to a minimum without in any way affecting the rigidity and resiliency of the support of the pane.

As shown in Fig. 5, the portion 1 of the

guide may be bent inwardly in arcuate form, which inwardly bent portions may either be continuous or intermittent, depending upon the particular service for which the guide is 5 designed, and the portions 4, which are bent inwardly of the guides, are further shown curved, in contradistinction to the straight portions of the form illustrated in Fig. 1, which form of construction, along with the 10 formation of the pane edge engaging means, provides a resilient support for the window pane in a manner peculiarly applicable to certain forms of installation.

The form of guide shown in Fig. 6, which 15 is a further modification of the form illustrated in Fig. 1, has the portion 10 thereof formed flat similarly to portion 1 of Fig. 1, although the struck-up portions 6 are omitted in this form of construction and the re- 20 silient edgewise support for the pane is provided for in this form of construction by having the edges 11 of the portions 4 rebent as indicated so as to engage the edge of the pane.

25 In Fig. 7 a further modification of the guide as shown in Fig. 1 is illustrated, which modification consists primarily in the sharp angularity with which the flat parts are disposed, such angularity affording some features of support which are not found in any other forms of construction. In this particular form the portion corresponding to 1 of Fig. 1 is bent inwardly somewhat similarly to the form illustrated in Fig. 5, although 30 here the groove or channel formed on the outer face consists of substantially flat outwardly converging walls 12 which are joined by a flat pane edge contacting portion 13 and the portions 14 which correspond to portions 4 of the forms heretofore described extend inwardly at a sharp angle and are preferably formed of straight elements so as to present a less resilient support for the sides of the pane.

45 In Fig. 8 a further modification of the form of my invention is shown, in which the portion of the guide which contacts with the base of the guide receiving groove is bent inwardly as at 15 so that support for the guide is 50 furnished at spaced points 16 and the edges of the one-piece element are bent outwardly to contact with the inner faces of the groove, in contradistinction to being bent inwardly to contact with the pane of glass as described 55 in connection with the previous forms of construction. The edges 17, which in this form of construction contact with the sides of the guide receiving groove, have projecting inwardly therefrom arcuate elements 18 60 which resiliently engage the sides of the pane and maintain such pane in proper position and permit a free and easy movement of the pane longitudinally with respect to the guide.

65 It will be noted in connection with the description of the guide comprising my in-

vention that the several modifications of the preferred form of construction that like ordinals have been employed to designate similar parts of the various forms so as to more readily understand the modifications 70 which have been made in such preferred form without departing from the principles of my invention. With the employment of the guide comprising my invention the pane is resiliently secured in the window or door 75 jamb in such a manner that a sliding thereof longitudinally with respect to the guide is easily accomplished and, further, the pane is so supported that a rattling or a loosening thereof will not occur during the life of 80 the guide.

A further description of the principles of my invention is believed unnecessary for those familiar with the art, suffice it to say that numerous advantages and desirable 85 characteristics are present in the forms of construction herein illustrated which it is believed are so apparent that a reiteration thereof is unnecessary.

90 Other modes of applying the principle of my invention may be employed instead of the one explained, change being made as regards the structure herein disclosed, provided the means stated by the following claim or the equivalent of such stated means 95 be employed.

I therefore particularly point out and distinctly claim as my invention:

100 In combination with a window casing having a groove therein, a glass supporting member comprising a single strip of resilient sheet metal bent to provide a plurality of longitudinally extending ribs engaging the bottom of said channel along lines spaced from the sides of said groove reentrant edges engaging 105 opposite faces of said glass and rebent for reinforcement adjacent the line of such engagement, and portions engaging the opposite side of said groove.

110 Signed by me this 20th day of March, 1930.
JOHN M. KELLER.
